UNITED STATES PATENT OFFICE

WILLIAM D. COLLINS, OF EVANSVILLE, INDIANA, ASSIGNOR TO HERCULES PRODUCTS, INC., OF EVANSVILLE, INDIANA, A CORPORATION OF DELAWARE

AUTOMOBILE BODY

Application filed April 13, 1929. Serial No. 354,747.

My invention relates to automobile business bodies and particularly to closed bodies.

In previous constructions, there have been used a great number of wooden members forming a wall section with a number of vertical wood members adjacent thereto and forming reinforcements for the walls. These vertical wooden members project into the inside space of the body and limit the effective volumetric capacity. In lieu of this construction, I propose to use ply-wood boards attached to strong longitudinal members with widely spaced metal reenforcing bars extending vertically and secured to the longitudinal members. By this means I obtain a greater effective volume of the body enclosure and the appearance is greatly improved.

The invention will be explained with reference to the accompanying drawings, forming a part of this specification and showing a preferred form of the invention, whereof:

Fig. 1 is a transverse section of a body wall;

Fig. 2 is a side view of part of a wall; and

Fig. 3 shows a body with the invention applied thereto, part being in section.

Reference character 10 designates an automobile business body comprising a side wall 11, a floor 12 and a roof 13. The wall comprises a lower longitudinal member 14 made of wood, a middle longitudinal member 15 made of wood, and an upper longitudinal member 16 made of wood. The outside upper edge of member 14 is cut away and the outside lower edge of member 16 is cut away by the width of ply-wood boards 17 and 18. Member 15 is arranged and aligned so that boards 17 and 18 are in alignment by being secured to members 14, 15 and 16.

Fastened to member 15 on the outside thereof is a metal strip 19 having a flange 20. A panel plate of metal 21 has a lower flange which is hooked under the flange 20 after which plate 21 is secured to the upper side of member 16. A panel plate 22 of metal has an upper projection which fits under flange 20. Plate 22 is secured under member 14. By this arrangement the outside metal plates are secured to member 15 without any exposed nails or screws.

Extending vertically of the body at widely spaced intervals are metal reenforcing bars 24. These bars are bent inwardly at the bottom and secured to the floor 12 by bolts 25 and screws 26. These bars are secured to members 14, 15 and 16 by screws and serve to reinforce the wall. The bars are secured to the roof section by means of bolts 30. Members 14, 15 and 16 project inwardly into the body beyond the ply-wood boards and spacing pieces 27 are arranged between reenforcing bars 24 and the ply-wood boards. Screws pass through bars 24 and into the spacing members. The bars are flanged at 29 to each side of the spacing members.

By using the metal bars, I am able to use the smooth ply-wood boards. These boards are not rigid but are smooth and give a neat appearance. Rigidity is supplied by means of the metal reenforcing bars. By using relatively heavy metal reenforcing bars I am able to space the same much more widely apart than would be possible by the use of wooden reenforcing members. Furthermore the appearance is made neat by the combined use of the ply-wood boards, or like smooth boards, and the metal reenforcing bars, while effective body space is saved over what would be the case if wooden vertical bars were used. Furthermore the use of the metal bars facilitate the assembly of bodies of this kind where the floor, roof and side walls are shipped separately from a factory.

What I claim is:

1. In body construction top, bottom, and side members, the latter comprising longitudinal wooden frame members, wooden spacing pieces between said frame members, metal reinforcing bars connecting the top, bottom, and longitudinal frame members, said metal reinforcing bars having their opposite edges bent to form flanges encasing said spacing pieces.

2. In body construction longitudinal frame members, upright spacing pieces therefor, reinforcing bars attached to and connecting said frame members and spacing pieces and having opposed edges between the longitudinal members bent laterally in engagement with the spacing pieces, said reinforcing bars

having their upper and lower extremities formed for attachment to the top and bottom of the body.

3. In body construction top, bottom and side members, the latter comprising longitudinal wooden frame members, wooden spacing pieces between said frame members, metal reinforcing bars connecting the top, bottom and longitudinal frame members, said metal reinforcing bars each having a portion extending laterally outward to form a reinforcement for the body structure.

In testimony whereof I have affixed my signature.
